BENJAMIN G. RAND, OF NORTH TONAWANDA, NEW YORK, ASSIGNOR TO REMINGTON RAND INC., OF BUFFALO, NEW YORK

ROTARY INDEX

Application filed July 11, 1930. Serial No. 467,304.

This invention relates to indexing devices, and it has particular reference to an index of the rotary type wherein any one of a number of index cards or panels may be brought to view by movement of the cards in a fixed closed path.

Heretofore rotary indexes have been employed in which a number of cards were mounted in substantially radial fashion about a rotatable axis. In one form, there has been provided a vertical spindle, rotatably mounted on a bed plate or table, having hingedly secured thereto a plurality of index plates or leaves, any one of which could be brought to view by rotation of the index plates as a unit with the spindle, and then examined at leisure by rotation or swinging about its own axis or hinge.

In large offices it is necessary to have a larger number of index cards constantly available for reference than this type of holder will readily accommodate. Heretofore it has been necessary to meet this demand either by providing a large number of units, or making the units so large that they were unwieldy. In either event, the installation was costly and required an excessive amount of floor space. The employment of a single index holder is additionally preferable because of operating conditions, and at times it may be expeditious to have a number of persons simultaneously consulting different cards in the same unit.

The present invention contemplates an index construction which is especially adapted for use under such conditions, and it comprises, in essence, a pair of spaced spindles or rotatable axes, between which extend endless or continuous flexible bands having hingedly connected therewith means for mounting the several plates. The spindles are disposed a sufficient distance apart to provide space therebetween for a great number of plates or cards, which extend outwardly from the continuous bands and are separated in order that any one of them may swing about on its individual axis, to permit inspection at any position about the periphery of the band.

These and other objects and advantages

will become apparent from a perusal of the following description of a device embodying the principles of the invention, illustrated in the accompanying drawings wherein:

Fig. 1 is a perspective view, cards at one end of the device being swung about their axes of attachment to permit an examination thereof.

Fig. 2 is an enlarged vertical section taken through one of the spindles.

Fig. 3 is a fragmentary detail sectional view showing means intermediate of the spindles for supporting the upper endless member and the means of attaching to the latter the index plates.

Fig. 4 is a plan detail of a section of the endless member and attached index plates; and

Fig. 5 is a view similar to Fig. 4, showing a modified construction.

As shown in Fig. 1, the index comprises a table or bed 10, of greater length than width, upon which is disposed, adjacent each end, a socket or foot bearing 11 threaded to receive the lower end of a supporting post 12. Sleeves or tubular shafts 13 are rotatably mounted on the posts, being supported at their lower ends by antifriction thrust bearings 14. Sprockets 15 and 16 are fixedly secured at each end of the shafts by keys 17, and about the ends of and between the sprockets extend the endless flexible members 18 and 19. These preferably comprise metal link chains, interfiting with the sprocket teeth, and the links thereof having outwardly extending lips 21.

Positioned above and beneath the sprockets 15 and 16 are cover and supporting plates 22 and 23, the latter resting on the table 10 and supporting the anti-friction bearings 14, and the upper plates 22 being supported on the shafts 13 and the sprockets 15. Knurled caps 24 are threaded to the upper rod ends to secure the plates in assembled relation. As illustrated the cover plates may extend over the entire area defined by the chains, to prevent the ingress of dirt and to enhance the appearance of the device. As the plates 22 and 23 are of similar construction, one being inverted from the other in assembly, the

structure of one only need be described. As shown in Fig. 3, the upper plate is provided with a channel-way 25 for enveloping the endless chain 18, each channel-way being 5 formed by an angle member 26 having a horizontal portion 27, acting in conjunction with a peripheral flange 28 depending from the plate, the flange and the portion 27 being spaced to provide a longitudinal recess for 10 the chain link extensions 21.

It will be seen that the chain members are supported intermediate of the sprockets by these channel forming parts, preventing sagging and undue strain thereof, which, inasmuch as the chains are of relatively great 15 length, is an important provision. The upper chain 18 will rest directly on the angle portion 27 while the lower chain 18 will be supported by engagement of the extensions 21 20 on the upstanding flange 28 of the lower plate member.

The index units 30 comprise cards or strips 31 mounted upon panel or plate members 32, which have upper and lower wire extensions 25 33 and 34. These have respectively upwardly and downwardly extending end portions for engagement into apertures in the extensions 21 of the upper and lower chain members. As depicted in Fig. 2, the extensions are so 30 spaced that the index units may have a limited vertical movement relative thereto, so that by raising the units the wire extension 34 may be disengaged from the lower chain extensions.

35 In assembly, the chains 18 and 19 may be threaded through the channel-ways 25 by temporarily deforming a portion of the flanges 28 or by providing a break in the flange to form a fitting opening, or by disconnecting 40 certain links. The chains are thus concealed from view and dirt by the plate flanges and are supported and guided intermediate of the sprockets by the flanges in conjunction with the angle members 26. The index units 45 30 are then mounted between vertically aligned lips 21 and the device is ready for use. In operation, it will be found expedient to view the indexes from the narrow end of the table 10 in order to conserve floor space, 50 but if the table is very long the indexes may be viewed from the side of the table, as by more than one operator.

In the modified chain link construction 55 shown in Fig. 5, the links of chain 40 are provided with enlarged outwardly extending lips 41. Each of these lips have longitudinal slots 42 in which a plurality of index plate extensions are engaged for pivotal and slight longitudinal movement. The slots are of such 60 length that sufficient clearance is provided between the index units 30 attached to any one extension lip 41, that any one of such plate members may be viewed by moving the plate members engaged in the slots longitudinally and angularly thereof.

It will be noted that the capacity of the device is very large, as the sprockets may be widely spaced, and that the load on the chains is borne by the cover plates, while the tubular shafts or sleeves will keep the upper and lower chain lips in constant alignment and insure coordinated movement of the chains. The device may be operated either by hand or automatic means.

70 It will be understood that the specific device described may be modified in various structural details, and it is intended that the invention should be commensurate with the scope of the following claims.

75 What is claimed is:

1. An index comprising a table having a pair of spaced spindles mounted thereon, a chain extending between the spindles, a cover plate overlying the chain and provided with a depending flange member for supporting 80 the chain between the spindles, and index units connected to the chain.

2. An index comprising a table having a pair of spaced spindles mounted thereon, sprockets mounted on the spindles at the ends 90 thereof, chains extending between the sprockets, lips projecting from the chains and adapted to receive index units, a cover plate overlying the chains, said cover plate being provided with depending flanges forming an 95 envelope around the chain and supporting the weight thereof.

3. An index comprising an elongated table having spindles mounted at opposite ends 100 thereof, sprockets mounted on opposite ends of the spindles, chains extending between the sprockets, said chains being provided with projecting and apertured lips formed on the links thereof, index panels formed with offset pintles hingedly mounted between the lips, 105 a cover plate mounted between the spindles and formed with a depending marginal flange surrounding the chain, and an interior flange between the sprockets supporting the chain, 110 said marginal flange and interior flange being spaced to form an aperture for the projection therethrough of said lips.

4. An index comprising a plate having channels opening at its outer edges, a flexible member movably supported in said channels, 115 and index units hingedly mounted on said flexible members.

5. In an index, an endless flexible member 120 movable in the path of its periphery, supporting and guiding means for said member, projections on said member having elongated slots, and a plurality of index units having extensions engaged in each of said slots.

6. In an index, spaced channel portions 125 opening outwardly, a wheel mounted adjacent to the ends of and between said portions, an endless flexible member mounted in said channel portions and in engagement with said wheel, and index units mounted on said flexible member.

7. An index comprising a pair of spaced parallel spindles, a pair of spaced sprockets on each spindle, means connecting each pair of sprockets for unitary rotating movement on their respective spindle, a pair of spaced plates each extending between the spindles adjacent each pair of opposite sprockets and mounted on the spindles to connect the same, guide means on each plate, chains mounted 10 on and extending between opposite sprockets and slidably mounted on the guide means of the adjacent plate for supported parallel movement relative to each other, spaced mounting means projecting from the chains 15 beyond the guide means, the mounting means on one chain being in alignment with the mounting means on the opposite chain, and a plurality of index devices each mounted for hinging movement between opposed mounting means.

8. An index comprising a pair of spaced parallel spindles, a pair of spaced sprockets mounted on each spindle, guide means extending between the spindles adjacent each 25 pair of opposed sprockets, chains mounted on and extending between the opposed sprockets and slidably mounted on the adjacent guide means for supported parallel movement relative to each other, spaced recessed 30 lips projecting from the chains beyond the guide means, the lips on one chain being in alignment with the lips on the opposite chain, an index panel between each pair of opposed 35 lips, each panel having oppositely extending pintles, the upper pindle being of greater length than the lower pindle whereby the pintles of the panel can be mounted between the recesses in opposed lips and be adapted for vertical movement to disengage the lower 40 pindle for removing the panel.

9. An index comprising a pair of spaced supporting means formed with channels, lineally movable members in each of said channels, means controlling operation of said 45 members to secure movement thereof in unison, a plurality of index panels extending between said members, and detachable connections between said panels and members.

10. An index comprising a pair of spaced plate members having channels opening at their outer edges, a lineally movable member in each of said channels, means controlling said members for operation in unison, and a plurality of index panels extending 55 between said members and detachably connected thereto through the openings in said channels.
